UNITED STATES PATENT OFFICE

154,640

DESIGN FOR A GROCERIES TRUCK

Travis M. Sasser, Terrace Park, Ohio, assignor to Shipping Room Suppliers, Inc., Cincinnati,
Ohio, a corporation of Ohio

Application June 26, 1948, Serial No. 147,238

Term of patent 14 years

(Cl. D14—3)

To all whom it may concern:

Be it known that I, Travis M. Sasser, a citizen of the United States, residing at Terrace Park, in the county of Hamilton and State of Ohio, have invented a certain new, original, and ornamental Design for a Groceries Truck, of which the following is a full, clear, and exact description, reference being had to the accompanying drawings, forming a part thereof.

In the drawings:

The characteristic features of my design reside in the portions shown by means of full lines in the drawings.

I claim:

The ornamental design for a groceries truck, as shown and described.

TRAVIS M. SASSER.
